CLAIM

The ornamental design for a teleconferencing transmission terminal, as shown and described.

DESCRIPTION

FIG. 1 is a front elevational view of a teleconferencing transmission terminal showing our new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front, top and right side perspective view thereof;

FIG. 8 is a front elevational view thereof with the cover for function keys in raised, oblique position;

FIG. 9 is a top plan view thereof with the cover raised; and

FIG. 10 is a right side elevational view thereof with the cover raised.
